UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-RIGGING YOKE.

1,286,733.

Specification of Letters Patent.

Patented Dec. 3, 1918.

Application filed August 19, 1916. Serial No. 115,748.

To all whom it may concern:

Be it known that I, JOHN F. O'CONNOR, a citizen of the United States, residing at Chicago, in the county of Cook and State of Illinois, have invented a certain new and useful Improvement in Draft-Rigging Yokes, of which the following is a full, clear, concise, and exact description, reference being had to the accompanying drawings, forming a part of this specification.

This invention relates to improvements in draft rigging yokes.

One object of the invention is to provide a detachable connection between a draw bar and a one piece yoke.

Another and more specific object of the invention is to provide a detachable connection between a one piece yoke and a draw bar, wherein the parts may be assembled or disassembled while the yoke is in position on the car.

In the drawing forming a part of this specification, Figure 1 is a side elevation of a portion of a draw bar and a yoke showing my improvements in connection therewith. Fig. 2 is a transverse, vertical section taken substantially on the line 2-2 of Fig. 1. Fig. 3 is a horizontal sectional view taken substantially on the line 3-3 of Fig. 1. And Fig. 4 is a detail perspective of the rear end of the draw bar employed in the construction illustrated in Figs. 1, 2, and 3. Fig. 5 is a view corresponding to Fig. 1, illustrating another embodiment of the invention. And Fig. 6 is a sectional view corresponding to Fig. 2 and taken on the line 6-6 of Fig. 5.

In said drawing and referring to the structure illustrated in Figs. 1 to 4, 10 denotes the shank of a coupler or draw bar, the same being substantially rectangular at its rear or butt end and provided at the top and bottom with transversely extending shoulders 11 and 12. The shoulders 11 and 12 are extended at their sides beyond the sides of the coupler butt, as indicated at 13-13. Intermediate the extended ends 13-13, the sides of the draw bar butt are provided with a pair of spaced rectangular lugs 14-14 which are extended to a plane flush with the ends of the extensions 13-13. The yoke A comprises an upper arm 15, lower arm 16, rear connecting portion 17, and a rectangular hood or head at the forward end. The hood or head comprises an upper wall 18, side

walls 19-19, and downwardly offset lower wall 20. The upper wall 18 of the hood is provided with a transversely extending shoulder or gib 21 and the inner faces of the side walls 19 are provided with three inwardly extended lugs 22-22 equally spaced and terminating so as to provide clearance for the sides of the draw bar butt when the latter is inserted. The lugs 22 are spaced to correspond to the vertical dimensions of the lugs 14-14 and extensions 13-13 on the draw bar, four of such spaces being provided on the inner face of each side wall of the yoke hood. The arrangement is such that the butt of the draw bar 10 may be inserted within the hood of the yoke, the extensions and lugs 13 and 14 of the draw bar passing through the spaces between the lugs on the side walls of the hood. The length of the lugs 22 on the hood is clearly indicated in Fig. 3 and equals approximately half the length of the side wall of the hood. The length or longitudinal dimensions of the extensions 13 and lugs 14 on the draw bar butt correspond substantially to the lengths of the lugs 22. After the draw bar has been inserted sufficiently within the hood of the yoke so that extensions 13 and lugs 14 pass beyond the lugs 22 of the hood, the draw bar butt is then raised or elevated so that the upper shoulder 13 will engage the gib 21 and the lugs 14-14 and lower shoulder 12 will engage behind the lugs 22-22 on the inner faces of the side walls of the hood. To hold the draw bar in this elevated position, I have provided a transversely extending locking block 23 which is insertible through recesses in the side walls of the hood. Said locking block 23 comprises a lower horizontal supporting plate or portion 24 and an upturned angular flange 25 which engages the lower shoulder 12 of the draw bar butt. On one end, the locking block 23 is provided with a depending lip 26 which limits the transverse movement of the block 23 relatively to the hood, and at its other end, the block 23 is perforated to receive the cotter 27 for retaining it in position.

From the preceding description, taken in connection with the drawing, it is apparent that I have provided an efficient and durable arrangement for connecting the draw bar and yoke and one which may be readily assembled and disassembled without disturbing the parts of the gear proper.

In the construction illustrated in Figs. 5 and 6, the draw bar 110 has the butt thereof formed of substantially pyramidal form with inclined sides 30-30 and horizontal base 31. The yoke A' is provided at its forward end with a correspondingly shaped hood, the latter having inclined side walls 32-32 and downwardly offset bottom wall 33. Each of the side walls 32 is provided 10 with an inwardly extended flange or gib 34 and across the top of the hood is a similar gib or flange 35. The size of the triangular shaped opening formed by the upper face of the lower wall of the hood and the edges 15 of the gibs or flanges 34 correspond to the size and shape of the pyramidal butt of the coupler. In assembling the parts, the butt of the coupler is inserted in a low plane within the hood of the yoke. After the 20 pyramidal butt has passed beyond the gibs or shoulders 34 and 35 of the hood, the draw bar butt is then elevated and it is apparent that the shoulders formed at the front of the pyramidal butt will engage behind the gibs 25 or shoulders 34 and 35. The draw bar butt is held in this elevated and operative position by means of a transversely extending key 36 which is inserted laterally through suitable recesses in the side walls of the 30 hood, which key engages the lower horizontal face of the draw bar butt. The key is held in position by means of a cotter 37.

I claim:

1. In a device of the character described, 35 the combination with a yoke having parallel arms and a hooded forward end, all integrally formed of a draw bar having a butt insertible longitudinally within said opening, the inner faces of the side walls of said 40 hood being provided with a series of spaced

inwardly extending shoulders and the draw bar butt being provided on the side faces thereof with correspondingly spaced, laterally extended integral shoulders, the spacing being such that the shoulders of the 45 draw bar butt are adapted to pass between those of the hood when the butt is inserted in one plane, said shoulders engaging when the butt is shifted vertically to another plane relatively to the yoke. 50

2. In a device of the character described, the combination with a cast yoke having an integral hood at its forward end adapted to receive therewithin the rear end of a draw bar, said hood having integral, rearwardly 55 facing shoulders on the inner faces of the sides of the hood, of a draw bar having the rear end thereof formed with integral forwardly facing shoulders on the sides thereof, the vertical interior height of the hood of 60 the yoke being greater than the vertical height of the rear end of the draw bar and thereby adapting said rear end to be inserted within the hood when the draw bar is in a plane lower than that normally occupied 65 by it with respect to the yoke when in operative condition, said shoulders on the draw bar being arranged to pass between the shoulders of the hood when said draw bar is in said relatively lower plane, the shoulders 70 of the draw bar and hood engaging when the draw bar is elevated within the hood, and detachable means arranged to engage the under side of the rear end of the draw bar to support the latter in its elevated 75 position within the hood.

In witness that I claim the foregoing I have hereunto subscribed my name this 14th day of August, 1916.

JOHN F. O'CONNOR.
